DESIGN FOR AN AUTOMOBILE DOOR AWNING

Ernest R. Scott, Oklahoma City, Okla.

Application October 18, 1937, Serial No. 72,286

Term of patent 7 years

To all whom it may concern:

Be it known that I, Ernest R. Scott, a citizen of the United States, residing at Oklahoma City, in the county of Oklahoma and State of Oklahoma, have invented a new, original, and ornamental Design for an Automobile Door Awning, of which the following is a specification, reference being had to the accompanying drawing, forming part thereof.

Figure 1 is a perspective view of an automobile door awning illustrating my new design. The

view is taken looking at the inside of the awning;

Figure 2 is a perspective view showing the outside appearance of the awning;

Figure 3 is a top plan view of an awning showing my new design; and

Figure 4 is a transverse midsectional view thereof.

I claim:

The ornamental design for an automobile door awning, as shown.

ERNEST R. SCOTT.
